UNITED STATES PATENT OFFICE.

HORACE F. HODGES, OF CHELSEA, MASSACHUSETTS.

ROTARY MOTOR.

SPECIFICATION forming part of Letters Patent No. 271,459, dated January 30, 1883.

Application filed May 26, 1882. (No model.)

To all whom it may concern:

Be it known that I, HORACE F. HODGES, a citizen of the United States, residing at Chelsea, in the county of Suffolk and State of Massachusetts, have invented certain new and useful Improvements in Rotary Motors; and I do hereby declare that the same are fully described in the following specification and illustrated in the accompanying drawings.

This invention relates to improvements on that class of engines or motors in which the piston rotates on a fixed axis, which axis is a shaft connected with the work to be done without the intervention of a crank. It is reversible, and possessed of an automatic cut-off, by which its speed is governed. It is duplex in its action, and can be used either as a high or low pressure engine and with or without condensers. In my engine or motor I avoid all dead-centers, either partial or complete, and the steam acts continuously upon a constant and invariable area of the rotary piston. It is also provided with a perfectly-balanced valve, the same being an oscillating tube having ports on opposite sides, which, when open, lead into a common chamber, as will be further described, reference being had to the accompanying drawings, in which—

Figure 1 represents an end elevation of my improved motor. Fig. 2 represents a sectional side elevation as seen from X in Fig. 1, the bearing for the rotary axle being shown as removed. Fig. 3 represents a vertical section on the line A B, shown in Fig. 1. Fig. 4 represents a horizontal longitudinal section on the line C D, shown in Fig. 1. Fig. 5 represents a vertical section of the steam-chest on the line E F, shown in Fig. 2. Fig. 6 represents an end elevation of the mechanism for imparting an oscillating motion to the induction-valve to effect the cut-off. Fig. 7 represents a horizontal section through the cylindrical induction-port and tube-valve on the line G H, shown in Fig. 1, showing how I employ the pressure of the steam to instantly close the valve at the point of cut-off. Fig. 8 is a diagram showing the method of determining the outline of the piston.

Similar letters refer to similar parts wherever they occur on the different parts of the drawings.

a is the cylinder, of equal thickness at nearly

all points, to secure equal expansion when heated, and thus preserving its rotundity.

b is the main shaft, which conveys the power generated to the point of delivery desired.

c is the piston, firmly attached to the shaft *b*, and of such shape on its outer periphery that its diameter through the center of its revolution is the same in all directions, while the length of its radii is different at different points. The sum of any two radii in a line with each other is equal to that of any other two radii in a similar position. In constructing said piston *c*, I first draw a circle, 1, Fig. 8, the diameter of which shall be equal to the diameter of the main cylinder less the greatest depth of the depression I wish in the piston *c*. I then divide said circle 1 into six equal portions of sixty degrees each, and separate the points 22, 33, 44, of said division into three pairs of two each. I next draw from one to another of the points in each pair an arc of a circle or ellipse, 5 5 5, preferably the former, the radius of which is such that its center or crown 6 shall be at a distance from the center of said piston *c* equal to the radius of the cylinder *a*, thus completing one-half—one hundred and eighty degrees—of the periphery desired. I then measure from contiguous points in each of the arcs already drawn, on a line passing through the center of said piston, a distance equal to the diameter of the circle 1, which three resulting curves complete the periphery as desired—viz., one without abrupt curves, and which gives nearly the same motion to the gates E E as is given to a connecting-rod by a crank or eccentric.

c' c' are annular flanges of the same outer diameter as the bore of the cylinder *a*, bolted to the two opposite ends of the piston *c*, as shown in Fig. 4. Said flanges are beveled on their outer circumference to fit against corresponding bevels on the insides of the packing-rings *c'' c''*, secured to the arms *c''' c'''* of the center pieces, *c⁴ c⁴*, which in form of hubs or sleeves surround and fit closely the shaft *b* for a portion of their lengths and project through the cylinder-heads *a' a'*. Stuffing-boxes *a'' a'' a''' a'''* serve to pack the joints between the hubs *c⁴ c⁴* and the cylinder-heads *a' a'* and between the hubs *c⁴ c⁴* and the main shaft *b*, as shown in Fig. 4.

c⁵ c⁵ are annular plates or disks surrounding

the shaft *b* and resting against the outer ends of the hubs *c*⁴ *c*⁴, and are the means, in connection with the screw-bolts *a*⁴ *a*⁴ and their nuts, by which the bevel-rings *c*² *c*² are held in steam-tight connection with the beveled annular flanges or plates *c*¹ *c*¹. Said bolts *a*⁴ *a*⁴ also serve, in connection with corresponding nuts, to set up the packings of the stuffing-boxes *a*² and *a*², similarly arranged and constructed in each end of the shaft *b*, as shown in Fig. 4. At the junction of the outer edges of the annular flanges or plates *c*¹ and beveled rings *c*² and inner bore of the cylinder *a* is arranged an annular packing, *a*⁵, in each end of the cylinder *a*, the latter being enlarged in its bore to receive such packing as well as the packing-ring *a*⁶, which is held in place by suitable means, and by these means all lateral leakage at such junction is entirely obviated, and any wear on the different parts can be taken up at will. The cylinder-heads *a*¹ *a*¹ are secured steam-tight to the ends of the cylinder *a* in the ordinary way.

*a*⁷ is an overflow-pipe leading from the space between the piston-packings *c*¹ *c*² and the cylinder-head *a*¹ in each end of the cylinder to the exhaust *f*⁶ for the purpose of conducting the surplus condensed water from said spaces to the exhaust.

From the piston *c* the shaft *b* extends outwardly in both ends sufficiently to be supported in the stationary bearings *d*¹ *d*¹, attached to the frame *d*, as shown in the drawings. *d*² *d*² are vertical webs secured to or cast in one piece with the base or frame *d*, which webs have in their upper edges semicircular flanged saddle-pieces *d*³ *d*³, in which the cylinder *a* is firmly held and secured by suitable means.

On two opposite sides of the cylinder *a* are rectangular projections or extensions *a*⁸ *a*⁸, through which are horizontal perforations *a*⁹ *a*⁹, as shown in Fig. 3. The lower sides of said projections *a*⁸ *a*⁸ are fitted to rest on the top of the horizontal extensions *d*⁴ *d*⁴ of the flanges *d*³ *d*³, and help to secure the cylinder *a* in its place and to prevent its rotation when under pressure.

e *e* are sliding gates or valves, which are adapted to move in a horizontal direction forward and back within the rectangular perforations *a*⁹ *a*⁹ and between the anti-friction rolls *c*¹ *c*¹, arranged on the top and bottom of said gates or valves *e* *e*, as shown in Fig. 3, said rollers *c*¹ *c*¹ being arranged in pairs and connected by suitable links or regulators, and upon which rollers the valves *e* *e* are properly balanced, so as to prevent a lateral strain on such valves and their outer connections. The gates or valves *e* *e* are provided at their sides with yielding packing-strips *e*² *e*², pressed outward against the sides of the perforations *a*⁹ *a*⁹ and annular flanges *c*¹ *c*¹ by means of suitable springs, *e*³ *e*³, as shown in Fig. 4, so as to prevent the steam from passing from one side of the gate to the other. The inner end of each gate or valve *e* rests against the outer periphery of the piston *c*, and the sides of said

gates, with their packing-strips *e*² *e*², move between the sides of the perforations *a*⁹ *a*⁹ and between the annular plates or flanges *c*¹ *c*¹, as shown.

To the outer ends of the projections *a*⁸ *a*⁸ are secured the steam-chests *f* *f*, through the center of which passes steam-tight the outer end of the gates or valves *e* *e*, which latter at this point terminate as rods *e*⁴ *e*⁴, passing through stuffing-boxes *f*¹ *f*¹ on the outside of the steam-chests *f* *f*, and are firmly secured, by means of adjustable check-nuts, as shown in Figs. 1, 3, and 4, to the cross-heads *e*⁵ *e*⁵, which latter are connected together by means of the rigid connecting-bar *e*⁶. The weight of the cross-heads *e*⁵ *e*⁵ and the connecting-bar *e*⁶ is supported on the rods *e*⁷ *e*⁷, attached to the upper ends of the cross-heads *e*⁵ *e*⁵, and adapted to slide within bearings in the upper part of the arches *e*⁸ *e*⁸, secured to the flanges *d*⁴ *d*⁴ for that purpose.

*e*⁹ is a cap-bar, which forms the caps for the bearings on the arches *e*⁸ *e*⁸, and extends and is secured to the projection *a*⁸ on the cylinder *a*, as shown in Fig. 3, to prevent a lateral motion of the arches *e*⁸ *e*⁸.

f *f* are the steam-chests, secured to the hollow projections *a*⁸ *a*⁸, and shown in section in Figs. 3, 4, and 5. *f* is the steam-chest, Fig. 5, consisting of the tubular valve-well *f*¹, the steam-galleries *f*² *f*², the reverse-cock *f*⁴, the galleries *f*³ *f*³, and the gate-passage with its stuffing-box. Steam from the opposite inlets from the tubular valve-well enters a common chamber by the passages *f*² *f*², and passes into either the upper or lower gallery *f*³, according to the position of the reverse-cock, which is so constructed that when its position is such as to allow live steam to enter one of the galleries *f*³ the exhaust-steam can pass from the other gallery *f*³ to the exhaust-port by the passage *f*⁵. The construction and arrangement as described have several advantages. It forms what in a reciprocating engine would be called "clearance," it being not the receptacle from which steam is admitted by valves to the cylinder, but a vestibule always open to said cylinder, and into which the steam enters after passing the valves, and through which the steam automatically passes as it is exhausted from the cylinder. Being closely connected to the cylinder, it is less exposed to condensation by radiation, and serves to equalize the temperature of the gate *e*, to which gate it also serves the purpose of a guide, in connection with the cross-head *e*⁵ and sliding rods *e*⁷. The live steam in the steam-chest, although always free to enter the cylinder, is never free to enter the exhaust till, having turned the piston one-third of a revolution, it passes out of the exhaust-gallery of the opposite steam-chest, and then only such portion of it as has passed into the cylinder during the stroke. The steam remaining in the chest can be allowed to work through the succeeding stroke by expansion alone, no steam being admitted from the valve. Upon the reverse-lever *g*, which is attached to the reverse-cock *f*⁴,

being pushed ninety degrees to the right in Fig. 1, the reverse-cock f^4 is turned correspondingly in such a manner that live steam from the passages f'' is diverted from the upper passage f''' to the lower passage f'''' , and the direction of the motion of the engine reversed, and when the cock f^4 is so turned the upper passage f''' is open to the exhaust $f^5 f^6$. By returning the lever g to its original position shown in Fig. 1 the course of the live and exhaust steam is reversed, as is also the motion of the engine. The steam-passages $f''' f''''$ communicate with the perforation a^9 on the upper and under side of the valve or gate e , as shown in Fig. 3, and from thence to the space between the piston c and the cylinder a adjoining, as shown in said Fig. 3, causing a rotation of the piston c in a direction according to the position of the cock f^4 .

f^7 is a hollow cylindrical balanced induction-valve, (shown in detail in longitudinal section in Fig. 7,) communicating with passages $f'' f''$ by means of side perforations, $f^8 f^9$, in the sides of said valve f^7 . The valve-openings f^8 are made somewhat wider than the openings f'' at their junction with the valve f^7 , and permit a rotary motion of one-third of a revolution of the said valve f^7 without closing the same. The bottom of the valve f^7 is made with an incline, f^9 , resting on a correspondingly-inclined seat in the bottom of the steam-chest f , so that any rotation of said valve f^7 from its point of rest for one-half of its revolution causes a forward motion of said valve, sliding on the square portion of the shaft f^{12} toward the induction-pipe f^{10} , which is resisted by the pressure of the steam in the valve.

h is a disk attached to the valve-shaft f^{12} for the valve f^7 , which disk is provided with a radial slot, h' . (Shown in dotted lines in Fig. 6.)

h'' is a pinion attached to one side of the eccentric-disk h^3 , both of which are free to rotate together on the shaft f^{12} . On the eccentric-disk h^3 is a circular strap or ring, h^4 , holding three pins or projections, one, h^5 , of which enters the slot h' of the disk h , as shown by dotted lines in Fig. 6, and the two others, $h^6 h^6$, extend in an opposite direction from the disk h^3 , and are placed one hundred and twenty degrees from the pin h^5 and from each other. They are conical toward the pin h^5 and cylindrical on the opposite side.

h^7 is a hub on the shaft h^{10} , having radial sockets $h^9 h^8 h^8$, one hundred and twenty degrees apart, in which are inserted the radial spokes $h^9 h^9 h^9$, held toward the eccentric strap h^4 by means of springs h^{12} , attached to the hub h^7 . The shaft h^{10} —one on each side of the shaft b —is located in suitable bearings, $h^{13} h^{13}$, and provided on its inner end with a bevel-gear, h^{14} , gearing into the bevel-gear b' , attached to the main shaft b , as shown in Figs. 2 and 4, and by which a rotary motion is imparted from the main shaft b to the hubs $h^7 h^7$.

b'' is a cam or eccentric on the main shaft b ,

which connects to and operates a Hodges regulator, i .

On each reverse-lever g is a short arm, g' , which is connected to a rod, g'' , the lower end of which is connected to a bell-crank, g''' , located in bearings g^4 , such bell-cranks $g''' g'''$ being connected together by means of the fulcrum-bar g^5 , upon which are located two fulcra, $g^6 g^7$, which are caused to move laterally by the motion of the reverse-lever g and its connecting mechanism.

l is a regulator-link attached at l' to the pressure-rod of the regulator i and to the shafts l'' and l''' by the opposing cranks, l^4 and l^5 , as shown in Figs. 2 and 5, and connecting-links $l^6 l^7$ at a point, l^8 , on the end of the regulator-lever l .

$l^9 l^9$ are fulcrum-rests on the under side of the bar l , and are the points occupied by the fulcra $g^6 g^7$, respectively, according to the motion of the engine.

On the shafts $l'' l'''$ are geared arcs $l^{10} l^{10}$, which engage with the pinions $h'' h''$ and control the positions of the eccentrics $h''' h'''$.

$h h$ are two plumber-blocks secured to the frame d for holding and supporting the various parts of the valve-gears in position.

The operation of my improved engine is as follows: Steam being admitted by a suitable valve simultaneously at induction-ports $f^{10} f^{10}$, it passes through one of the cylindrical valves $f^7 f^7$ (one of which is open at all times when the motor is at rest) and on the left in Figs. 2, 3, and 4 through the passages $f'' f''$ of the steam-chest f , over the reverse-cock f^4 , along the steam-passage f'''' , by the anti-friction rollers $e' e'$, (which are shaped to allow it,) into the space above the gate or valve e , and between the piston c and the cylinder a , where its pressure causes the piston c to revolve in the direction of the arrow shown in Fig. 3. As the piston c revolves, the gate e on the left in Fig. 3 retreats and then advances, following the varying radius of the piston c , while the gate e on the opposite side approaches the center of the piston c , and then recedes at exactly the same rate as the varying radius of the piston c determines. As the effectual area of piston c acted upon by the steam is equal to the sum of the areas of those portions of both gates $e e$ projecting within the inside of the cylinder a , it follows that as one gate e advances precisely at the same rate as the opposite gate retreats, this area is unvarying. As the piston c , and with it the shaft b and bevel-gear b' , revolves, causing bevel-gears $h^{14} h^{14}$, shafts $h^{10} h^{10}$, hubs $h^7 h^7$, and arms or spokes $h^9 h^9$ also to revolve in the course of their revolution, one of the spokes h^9 on the right of the motor engages with the cylindrical side of the pin h^6 , and is, with the eccentric-ring h^{11} , of which it is a part, the pin h^5 , the slotted disks h , and valve f^7 , rotated and steam allowed to pass through the valve f^7 , by its before-described course, to the reverse-cock f^4 , above the same, and along the lower passage f'''' , into the space under gate e .

and between the cylinder *a* and piston *c*, thus further rotating the latter in the direction of the arrow shown in Fig. 3. As the spokes *h*⁹ on the left in Fig. 3 are rotated, the pin *h*⁶, with which they are in contact by reason of the eccentric on which said pin *h*⁶ and eccentric *h*⁴ are revolved, recedes farther and farther from the center on which the hub *h*⁷ and spokes *h*⁹ revolve, and is thus slid outwardly along the said spokes *h*⁹ until, when it has completed one-third of a revolution, said pin or projection *h*⁶ is no longer retained by the spoke *h*⁹, said spoke passing beneath it, and as it impinges against the other pin *h*⁶ on its conical side the spoke *h*⁹, which is held forward by the spring *h*¹², is pressed to one side and goes over said pin. During the revolution of the mechanism, as thus described, with the cylindrical valve *f*⁷, the latter, by reason of its inclined seat *f*⁹, has been pushed forward on the square section of the shaft *f*¹² and against the pressure of the steam. Now, therefore, the mechanism being released by the passage of the spoke *h*⁹ under the pin *h*⁶, the steam forces the valve *f*⁷ backward and around to its original position, thus closing the valve. As it, with the pin *h*⁶, resumes its position, said pin engages the next spoke *h*⁹ of the hub *h*⁷, and is again released at the high point of the eccentric *h*³, and this is repeated three times during each revolution of the shaft *h*¹⁰, and as the shaft *h*¹⁰ revolves at the same rate as the piston *c*, this opening and closing of the valve *f*⁷ take place once for each steam-space on the piston *c*, and as this action is made to commence as the gate *e* commences to descend the incline on the piston *c* toward its center on either side, respectively, it follows that the valves *f*⁷ open and close alternately on opposite sides of the motor. The position of the pins *h*⁶ *h*⁶ is invariably the same when at rest, as they are connected by the rings *h*⁴ *h*⁴, pins *h*⁵ *h*⁵, and disks *h* *h* to the valves *f*⁷ *f*⁷, whose positions, when at rest, are at their lowest point on the inclined seat *f*⁹; but the releasing-point corresponds to the high point of the eccentricities *h*³ *h*³, which in their normal positions are half-way from one pin *h*⁶ to the other; but as the motion of the motor through the eccentric *b*² and the regulator *i* depresses the regulator-rod *i*¹ more or less, in proportion as the engine exceeds or falls short of the speed desired, it depresses more or less proportionately the point *l*⁰ on the regulator-link *l*, which link, resting at the point *l*⁰ on the fulcrum *g*⁶, causes the point *l*⁰ of said link to rise, which, by means of links *l*⁶ *l*⁷ and levers *l*⁴ *l*⁵, causes shafts *l*² and *l*³ to revolve, together with the geared arcs *l*¹⁰ *l*¹⁰ and pinions *h*² *h*², rotating the high point of the eccentric *h*³ *h*³ toward the resting-point of the pins *h*⁶ *h*⁶, thus causing the release of said pins at an earlier part of the stroke than before, and shortening the cut-off. The limit of this motion is one-third of a circle or the full length of the valve-stroke. As the piston *c* revolves, the steam entering the cylinder on one side of the motor is allowed to pass out

by the passage *f*³, closed to the live steam, on the opposite side, into the exhaust *f*⁵ *f*⁶, where it may be advantageously condensed in appropriate condensers, thus adding to the efficacy of the motor, or led to a second piston on the same shaft as the first, making a compound engine, or otherwise disposed of.

To reverse the motor the reverse-lever *g* is moved ninety degrees in its upper arc of rotation, which, by means of the reverse-cocks *f*⁴ *f*⁴, diverts the course of the live steam into the opposite passages, *f*³ *f*³, as also that of the exhaust-steam, and brings fulcrum *g*⁷ beneath regulator-link *l* at *l*⁰, moving fulcrum *g*⁶ clear of said link, whereupon the regulator *i*, on being depressed, causes a downward motion of point *l*⁰ on link *l*, and thus causing the eccentricities *h*³ *h*³ to be inclined in the opposite directions. As the piston *c* revolves in an opposite direction the opposite pin, *h*⁶, is engaged by the arm or spoke *h*⁹, and the other pin *h*⁶, on account of its conical face exposed, passes under said spoke by reason of the yielding of the spring *h*¹². By arranging the valves *f*⁷ *f*⁷ to act for every alternate steam-space on piston *c* only, the steam remaining in the passages between the valves *f*⁷ *f*⁷ and inner line of the cylinder *a* (which never is free to pass to the exhaust, as is the clearance in a reciprocating engine) acts on every alternate steam-chamber on the face of the piston *c* by expansion alone; or it can be still further employed by having each valve *f*⁷ open but once for each revolution of the piston *c*, when the live steam is used once to expanding steam twice, by this means forming a species of compound engine.

What I wish to secure by Letters Patent, and claim, is—

145

1. In a rotary motor, a piston, *c*, the periphery of which is formed by, first, three symmetrical curves or arcs of a circle or ellipse, the ends of which rest upon a circle drawn from the center of said piston, said arcs covering sixty degrees of the arc of said circle and placed sixty degrees apart; and, second, three symmetrical curves formed by measurements of a distance equal to the diameter of circle 1 from contiguous points in each of said arcs through the center of said piston, as specified and shown.

2. In a rotary motor, the combination of piston *c*, constructed according to the formula herein described, cylinder *a*, the reciprocating gates *e* *e*, the cross-heads *e*⁵ *e*⁵, and connecting-bars *e*⁶ *e*⁶, as and for the purpose set forth.

3. In a rotary motor, the combination of piston *c*, cylinder *a*, the reciprocating gates *e* *e*, anti-friction rollers *e* *e*, the cross-heads *e*⁵ *e*⁵, and connecting-bars *e*⁶ *e*⁶, as and for the purpose described.

4. In a rotary motor, the combination of piston *c*, cylinder *a*, the reciprocating gates *e* *e*, anti-friction rollers *e* *e*, cross-heads *e*⁵ *e*⁵, connecting-bars *e*⁶ *e*⁶, sliding rods *e*⁷ *e*⁷, and supporting-arches *e*⁸ *e*⁸, as and for the purpose described.

5. In a rotary motor, the combination of

cylinder *a*, piston *c*, constructed according to the formula herein described, reciprocating gates *e e*, and the steam-chests *ff*, arranged, constructed, and operating in a manner and for the purpose set forth.

5 6. In a rotary motor, the combination of cylinder *a*, piston *c*, constructed according to the formula herein described, reciprocating gates *e e*, steam-chests *ff*, and reverse-cocks *f¹ f⁴*, as and for the purpose set forth.

10 7. In a rotary engine, the steam-chest *f*, consisting of the tubular valve-well *f⁷*, the galleries *f¹¹ f¹²*, the reverse-valve *f⁴*, the galleries *f¹³ f¹⁴*, the gate-passage, and the stuffing-box *f'*, arranged and operating in the manner and for the purpose set forth.

15 8. In a rotary motor, the herein-described releasing mechanism, consisting of bevel-gears *b¹ h¹⁴ h¹⁴*, shafts *h¹⁰ h¹⁰*, hubs *h⁷ h⁷*, radiating spokes *h⁹ h⁹*, springs *h¹² h¹²*, eccentrics *h³ h³*, eccentric-rings *h⁴ h⁴*, with pins *h⁵ h⁶*, slotted disks *h h*, and pinions *h² h²*, connected by shafts *f¹² f¹²* to valves *f⁷ f⁷*, as and for the purpose set forth.

20 9. In a rotary motor, the herein-described automatic cut-off mechanism, consisting of regulator *i*, pressure-rod *i'*, link *l*, fulcrum *g⁶*, connecting-links *l⁶ l⁷*, levers *l⁴ l⁵*, shafts *l² l³*, and geared arcs *l¹⁰ l¹¹*, in combination with *l¹* eccentrics *h³ h³*, as and for the purpose set forth.

10 10. In combination with the cylinder *a* and rotary piston *c*, the steam-chests *ff*, the cylindrical inclined valve-seats *f⁹ f⁹*, and the cylindrical valves *f⁷ f⁷*, having correspondingly-inclined ends, in combination with the releasing mechanism, as shown and described. 35

11. In combination with cylinder *a*, piston *c*, and shaft *b*, the annular rings *c' c'*, the bevel-rings *c'' c''*, the center pieces, *c''' c'''*, with their hubs *c⁴ c⁴*, the stuffing-boxes *a⁵ a⁵*, the cylinder-heads *a' a'*, pressure-disks *c⁵ c⁵*, stuffing-boxes *a'' a'''*, and screw-bolts *a⁴ a⁴*, as set forth. 40

12. In a rotary motor, the combination of cylinder *a*, frame *d*, webs *d'' d'''*, and flanged saddle-pieces *d''' d'''*, as described, and for the purpose set forth. 45

13. In a rotary motor, the arrangement of valves so as to allow live steam to enter the spaces on piston *c* alternately or less often, 50 and making the steam remaining in the steam-chest below the valve *f⁷* work by expansion alone on the remaining steam-spaces of the piston, as described.

In testimony whereof I have affixed my signature in presence of two witnesses. 55
